(57) **CLAIM**

The ornamental design for an optical fiber cutter, as shown and described.

DESCRIPTION

FIG. 1 is a front view of the optical fiber cutter, showing the new design;

FIG. 2 is a rear view of the optical fiber cutter;

FIG. 3 is a top plan view of the optical fiber cutter;

FIG. 4 is a bottom view of the optical fiber cutter;

FIG. 5 is a right side view of the optical fiber cutter;

FIG. 6 is a left side view of the optical fiber cutter;

FIG. 7 is a top perspective view of the optical fiber cutter;

FIG. 8 is a bottom perspective view of the optical fiber cutter;

FIG. 9 is a front view of the optical fiber cutter, with a cover open;

FIG. 10 is a top plan view of the optical fiber cutter, with the cover open;

FIG. 11 is a perspective view of the optical fiber cutter from above, with the cover open;

FIG. 12 is a front view of the optical fiber cutter, with a slide portion moved;

FIG. 13 is a rear view of the optical fiber cutter, with the slide portion moved;

FIG. 14 is a top plan view of the optical fiber cutter, with the slide portion moved;

FIG. 15 is a bottom view of the optical fiber cutter, with the slide portion moved;

FIG. 16 is a right side view of the optical fiber cutter, with the slide portion moved; and,

FIG. 17 is a perspective view of the optical fiber cutter, in use. The broken lines showing various elements of the optical fiber cutter are included for the purpose of illustrating non-claimed subject matter and form no part of the claimed design.
